WATERPROOF GUN COVER

Richard T. Cowley, Ellicott City, Md., assignor, by
mesne assignments, to the United States of America
as represented by the Secretary of the Navy

Filed Sept. 30, 1959, Ser. No. 843,606

4 Claims. (Cl. 89—37.5)

The present invention relates to protective seal construction and more particularly to the provision of a flexibly-mounted waterproof cover for the armament of seaplanes and the provision of means supported within the cover adapted to seal about the gun muzzles when the guns are not being fired.

In the construction of water-based bombers for one reason or another it often becomes necessary to locate gun turrets in such positions that they are either submerged at time or are at least subjected to a period of continuous spray and splash.

The provision of seal construction capable of preventing the entry of salt water or spray into the craft is of prime importance. Tests conducted by the Bureau of Ordnance of the Department of the Navy have proved that without the employment of extraordinary sealing means about the gun muzzles and other turret openings to prevent the access of salt water to the ordnance components, sufficient salt water enters the turret during landing and takeoff operations to render the guns totally inoperative. It becomes readily apparent that under these conditions, the entire defense system of such a water-based bomber can be rendered useless.

The present invention is directed to the combination of a flexibly-mounted waterproof gun cover and inflatable sealing means supported therein being arranged to seal about the gun muzzle (when the gun is not being fired) as, for example, when the gun turret is placed in stow position during landing and takeoff. Further, this combination provides for rapid conversion from the sealed to the unsealed position preparatory to firing.

The invention is not, of course, limited to use on guns mounted in aircraft gun turrets but is generally adaptable to use with armament mounted on vehicles in positions in which protection from the damage of sea water is required.

In freezing weather when the gun cover and seal are exposed to wave action or submersion during landing or takeoff there is the danger that the seal may freeze to the gun barrel. If the gun were to be fired while the seal is frozen thereto the recoil of the gun would tear the seal. To avoid this problem a heating element is provided adjacent the inflatable seal.

It is accordingly a major object of the present invention to provide a flexibly-mounted waterproof gun cover.

It is a further object of the present invention to provide inflatable means supported in said gun cover and adapted to seal about the gun muzzle.

It is an added object of the present invention to provide a heating element in conjunction with the inflatable seal to prevent the freezing of the seal to the gun muzzle and the subsequent tearing of the seal.

Other objects and many of the attendant advantages of this invention will be readily appreciated as the same becomes better understood by reference to the following detailed description when considered in connection with the accompanying drawings wherein:

FIG. 1 is an isometric view of a ball turret assembly with the turret and gun cradle shown at maximum elevation and waterproof covers for the turret guns;

FIG. 2 is an elevation view of a gun barrel with the gun cover thereover;

FIG. 3 is a front view of the gun cover in mounted position;

2

FIG. 4 is a section 4—4 of FIG. 3 taken through the front end of the gun cover;

FIG. 5 is section 5—5 of FIG. 3 taken through a check valve drain, and

FIG. 6 is section 6—6 of FIG. 3 taken through the means by which air is admitted to the seal.

Referring now to the drawings, wherein like reference characters designate like or corresponding parts throughout the several views, there is shown in FIG. 1 a typical ball turret assembly 11. Such a turret assembly is usually positionable in azimuth about upper turret support 12 and lower turret support 13. In addition the turret 14 is positionable in elevation whereby the freedom of movement permits the training of guns 16 over a wide pyramidal coverage.

In the event that such a turret assembly is to be utilized as the tail turret assembly in a seaplane there are times such as when the craft is sitting in the water, taking off or landing when this turret assembly is fully submerged or is at least subjected to splash and spray action. As has been stated above it is critical that the turret assembly be well-sealed against the entry of water under these conditions. Toward this end the barrels of gun 16 are increased in and protected by gun covers 17, 17.

Although the present description is directed towards a gun installation in an aircraft turret the same principles are applicable to any installation in which a gun barrel projects through a wall and it is desired to prevent the entry of fluids in the intervening space between gun barrel and the edge of the opening in the wall.

To more distinctly describe the construction and mounting of gun cover 17 reference is made to FIGS. 2, 3, 4, 5 and 6. Therein it is shown that gun cover 17 is flexibly mounted to an exterior surface of the turret, in this case gun cradle 18 by screws 19 passing through face plate 21 and fabric reinforced rubber gaskets 22, 23 arranged on either side of cover mounting flange 24. The outer end 26 of gun cover 17 supports inflatable seal 27, an elastic tube encircling gun barrel 20 or as shown gun muzzle 28. When inflated this elastic tube closes tightly about gun muzzle 28 preventing the flow of sea water between muzzle 28 and gun cover 17.

This actually amounts to sealing the intervening space between gun barrel 20 and opening 25 in the wall of gun cradle 18. As shown in FIG. 4 when seal 27 is deflated it retracts from muzzle 28. While the gun is being fired the seal is always in the retracted position to prevent damage of the seal due to the high temperatures encountered during firing. This positioning of seal 27 can be automatically provided for by correlating the control of the gun firing mechanism with means to release the fluid pressure in seal 27 whereby deflation and retraction of seal 27 will occur inherently. Means to effectuate such automatic control form no part of this invention, however. In order to prevent the freezing of seal 27 to muzzle 28 heating element 29 is provided adjacent seal 27 ready for such time as the weather conditions require its use. It is contemplated that heating element 29 is heated by electricity but the actual means employed forms no part of this invention.

Inflation of seal 27 is effectuated by arranging valve 31 to admit air under pressure from supply pipe 32 to conduit 33 from which the air passes through passages 34 and 36 into the interior 37 of seal 27. Deflation is achieved by arranging valve 31 to allow the air in seal 27 to escape through conduit 38.

Outer end 26 of gun cover 17 also provides a mount for spring-like fingers 39 which grip gun muzzle 28 from all sides and serve thereby to support the forward end of the gun cover 17. It can be readily seen therefore that the combination of fore and aft supports for gun

cover 17, that is, the resilient gasket mounting coupled with the spring grip mounting permits gun cover 17 to float thereby reducing the stress concentrations which would otherwise be induced therein if the unit were rigidly supported. The sources of such stress are the flight wind loads on cover 17; the high recoil and counter recoil accelerations of the gun barrel during firing and the high temperatures generated during firing. The casing of gun cover 17 is, of course, sufficiently stiff or rigid to support itself and retain its shape under flight wind loads. Because of the manner in which it is supported resulting in a reduction of stresses upon it, this casing can be made of lighter metal than would be necessary if it were rigidly supported.

In the event that moisture from condensation or other sources should collect within gun cover 17 provision is made for the drainage thereof without allowing the entry of sea water. FIG. 5 is a section taken through one-way valve 40. This valve is located in outer end 26 since being so located, when gun cradle 18 is placed in stow position (depressed to -45° elevation) any moisture in the gun cover will run to the low end thereof and be drained through passages 41 and 42 past ball valve 43 and out opening 44.

In operation, when the craft upon which the turret assembly 11 is installed is about to land in water, door 46 is moved into closed position, turret 14 is depressed to stow position with the underside of gun cradle 18 abutting door 46 and sidewalls 47 and 48 and seal 27 is inflated with air under pressure to seal about gun muzzle 28. Also, heating element 29 is actuated in the event that there is any danger of freezing.

Obviously many modifications and variations of the present invention are possible in the light of the above teachings. It is therefore to be understood that within the scope of the appended claims the invention may be practiced otherwise than as specifically described.

What is claimed is:

1. A gun cover comprising, in combination, a wall having an opening therethrough, a gun barrel projecting through said opening, elongated water-proof encasing means surrounding a portion of said gun barrel projection and comprising a rigid cylinder, said encasing means having an inner and outer end, an aperture in said inner and outer ends permitting said gun barrel to extend therethrough, sealing means in said outer end comprising an inflatable elastic tube encircling the gun muzzle closely when deflated and closing tightly thereagainst when inflated, and supporting means mounted in said inner and outer ends forming a water-proof juncture at both ends thereby sealing off the interior of said encasing means.

2. A gun cover as described in claim 1 in which said inner end of the encasing means is resiliently mounted on said wall, a plurality of rubber gaskets, said rubber gaskets providing a seal for said inner end and also resiliency thereto.

3. A gun cover as described in claim 2 wherein said cylinder is provided with means for draining condensation from the interior of said cylinder.

4. A gun cover as described in claim 1 wherein said outer end of said casing also has heating means mounted adjacent said inflatable sealing means.
